UNITED STATES PATENT OFFICE.

GUY B. WAITE, OF NEW YORK, N. Y.

CONCRETE-REINFORCEMENT.

1,239,649.

Specification of Letters Patent. Patented Sept. 11, 1917.

Application filed July 1, 1915. Serial No. 37,493.

To all whom it may concern:

Be it known that I, GUY B. WAITE, a citizen of the United States, and resident of New York, in the county of New York and 5 State of New York, have invented certain new and useful Improvements in Concrete-Reinforcements, of which the following is a specification.

The invention relates to improvements in 10 concrete reinforcement for building construction; and the object thereof is to provide a metal fabric or frame particularly adapted to receive and resist the strains common in this class of work. The object 15 also is to provide means for uniting the parts of the fabric in such manner as to preserve their normal shape and maximum strength, whereby contraction of the connecting joints, stretch and slippage of the 20 members and disintegration of the surrounding concrete is prevented, and the stresses in the composite structure localized to the best advantage.

In describing the invention in detail reference is had to the accompanying drawings, forming a part of this specification, and wherein like characters of reference are used to designate corresponding parts throughout the several views, and in which: 30 Figure 1 is a plan view of a metal reinforcement embodied in the present invention; Fig. 2, an end view thereof; and Fig. 3 is an enlarged view of a longitudinal tension-bar embedded in a concrete section, 35 showing in cross section the transverse tie-rods.

In the drawings, the numerals 1 designate a plurality of longitudinally extending metallic tension-bars, which are preferably 40 round in cross-section, and arranged in parallel relation to each other. Each bar 1 is provided with a series of elongated connecting slots 2, the same being elongated in the direction of the length of the bars, and 45 said slots are adapted to receive the transverse tie-rods 3.

In forming the elongated slots 2, the metal fiber of the tension-bars is spread laterally to form the expanded, outwardly projecting, and relatively long side-walls or arches 4, the ends of which gradually merge into the main portions of the bars. These 50 projecting side-walls or arches constitute anchorages and retain the bars against 55 movement or slip when they are embedded in the concrete, as shown at 5 in Fig. 3 of

the drawing, and by forming the connection slots relatively long, or longer than the diameter of the transverse rods, to provide the long arches, the full tensile strength of 60 the tension-bars is preserved, owing to the tapered ends of the slots causing the ends of the arches to gradually merge into the main portions of the bars. The gradual merging of the ends assures an unbroken continua- 65 tion of the metal fibers in the bars, and the necessary long spreading or separation required to form the elongated slots, will not displace any of the metal from the cross-section adjacent the slots. Therefore the 70 combined cross-sectional area of each pair of oppositely disposed arches remains equal to the cross-sectional area of the main or unseparated portions of the bar. Thus the tensile strength of the bars is not lessened as 75 the cross-sectional area is the same throughout the entire length of the bars, and the metal fibers are not ruptured by short and abrupt bending, but remain unbroken.

The transverse tie-rods 3 are fixed within 80 the connection slots by compressing the side-walls or arches upon the tie-rods after they have been positioned in the slots, and said tie-rods are furthermore secured against lateral displacement by the lock-loops 6, 85 formed by bodily bending the transverse rods adjacent to and on opposite sides of the tension-bars. As thus constructed the arched joint-sections of the tension bars will be obviously as strong in tension as the other 90 portions thereof, and the projecting anchorages will prevent movement of the bars in the concrete against compression or disarrangement under the ordinary working conditions. 95

I am aware that heretofore concrete reinforcements consisting of metal fabric have been employed wherein the members have been commonly united by twisting or looping one or both of the connecting parts. It 100 has been found in practice that connections of this kind serve ineffectually as anchorages inasmuch as they are quickly stretched and displaced under ordinary tension, resulting in a slippage of the rods, a disintegration of the concrete and a general weakening of the composite structure. 105

It will be obvious that the present invention, in overcoming these difficulties, provides a construction wherein a minimum 110 amount of material may be used for obtaining the required structural strength.

What I claim as my invention and desire to secure by Letters Patent is:

1. A reinforcement for concrete structures, comprising a series of metal tension bars arranged in parallel relation to each other, each of said bars being provided with a series of transverse openings which are elongated in the direction of the length of said bars and having relatively long arched portions on opposite sides of said openings, the cross-sectional area of each pair of arched portions being equal to the cross-sectional area of the main portions of the bars and the ends of said arched portions being gradually merged into said main portions to retain an unbroken continuation of the metal fibers and thereby preserve the full tensile strength throughout the entire length of the bars, and tie-rods extending at an angle to, and having the arches pressing thereon to fixedly secure in them the corresponding elongated openings of said bars.
2. A reinforcement for concrete structures, comprising a series of metal tension bars arranged in parallel relation to each other, each of said bars being provided with

a series of transverse openings which are elongated in the direction of the length of the bars and having relatively long arched portions on opposite sides, the cross-sectional area of each pair of arched portions being equal to the cross-sectional area of the main portions of the bars and the ends of said arched portions being gradually merged into said main portions to retain an unbroken continuation of the metal fibers and thereby preserve the full tensile strength throughout the entire length of the bars, and tie-rods extending at an angle to and engaged in corresponding elongated openings of the bars, said arches being compressed upon the tie-rods and said tie-rods being bent bodily to form loops at each side and adjacent to the tension bars to securely retain the bars and rods in position.

Signed at New York, in the county of New York and State of New York, this 29th day of June, A. D. 1915.

GUY B. WAITE.
